Attorney.

UNITED STATES PATENT OFFICE.

CHARLES T. E. GOULD, OF CHICAGO, ILLINOIS, ASSIGNOR OF ONE-THIRD TO EDWARD HILKER, OF CHICAGO, ILLINOIS.

SEWING-MACHINE.

1,079,485.

Specification of Letters Patent.

Patented Nov. 25, 1913.

Application filed September 13, 1912. Serial No. 720,205.

To all whom it may concern:

Be it known that I, CHARLES T. E. GOULD, a citizen of the United States, residing at Chicago, in the county of Cook and State 5 of Illinois, have invented certain new and useful Improvements in Sewing-Machines, of which the following, taken in connection with the drawings, is a description.

My invention has for its object the production of a bobbin holder for sewing machines of the class known as the rotary type, and is designed more especially to be used with a sewing machine having a sectional bed plate.

15 The principal object of my invention is to provide a bobbin holder which may be entirely inclosed within the casing covering the underthread mechanism; one which shall be very simple in construction and one 20 which when closed is securely locked in position forming a casing for the bobbin which is carried upon the end of the revolute shaft.

Other features of advantage of my invention will be hereinafter more fully explained and pointed out in the claim.

In the drawings forming part of this specification and in which like letters of reference indicate corresponding parts—

30 Figure 1 is a side elevation of my invention illustrating the bed plate of the machine in section; Fig. 2 is an enlarged view of the bobbin holder and locking mechanism; Fig. 3 is a similar view with the holder shown in section and the locking mechanism removed; Fig. 4 is an end elevation of the bobbin holder.

A, Fig. 1 illustrates the bed plate of the machine, A' the head, and B the needle 40 mechanism of a sewing machine, but which form no part of the present invention other than to illustrate the operation of the underthread mechanism, and will therefore not be further described.

45 B' is a rotary shaft operated by any suitable mechanism through the crank B² attached to one end thereof. Upon the opposite end is secured and revolves therewith the looper C. Fitting inside of the curve 50 formed by the hook of the looper is a bobbin

case c. Mounted upon the rotary shaft B' contiguous to the looper C is a cam or eccentric C' which operates against the under side of the feed C³ which extends through slots in the throat plate C⁴. This throat plate 55 C⁴ is removably secured to the bed plate A of the machine and is provided with a needle hole d² which is countersunk upon the under side thereof.

Hinged or pivotally secured to the flange 60 a on the under side of the throat plate, and extending over the end of the case c is a holder c' which is preferably circular in shape, Fig. 4. A pin c² extends across the holder and forms an abutment for the case 65 c, shown more clearly in Fig. 3. Secured to the flange a is one end of a leaf spring D, the opposite end of which has an opening therethrough which engages the projecting end of the pin c² to lock said holder c' in 70 closed position. The bobbin is thus held in the case c at the end of the revolute shaft B' directly beneath the throat plate C⁴, having the needle hole d² through which the upper thread is carried by the needle B, the 75 thread forming a loop through which the hook of the looper engages and carries it around to form the stitch with the lower thread, d.

I claim:

80 In a sewing machine, the combination of a revolute shaft, a bobbin case held in the end of the shaft, a throat plate located above said case, a circular bobbin holder pivotally secured at its upper part to the under side 85 of the throat plate, a pin extending across the center of said holder and projecting from the peripheral edge thereof, and a leaf spring secured at one end thereof to the under side of the throat plate and adapted for 90 engagement at its free end with said pin to lock the holder in closed position substantially as described.

In testimony whereof, I have hereunto signed this specification in the presence of 95 two subscribing witnesses.

CHARLES T. E. GOULD.
